[57] CLAIM

The ornamental design for a toy airplane launcher, substantially as shown and described.

DESCRIPTION

FIG. 1 is a top plan view of a toy airplane launcher showing my new design;

FIG. 2 is a left side elevational view thereof, the side opposite being substantially a mirror image;

FIG. 3 is a bottom plan view thereof;

FIG. 4 is a front elevational view thereof; and

FIG. 5 is a rear elevational view thereof.
